UNITED STATES PATENT OFFICE.

SIVERT MOE, OF CHICAGO, ILLINOIS.

MANGLE.

No. 909,312.

Specification of Letters Patent.

Patented Jan. 12, 1909.

Application filed November 16, 1906. Serial No. 343,678.

To all whom it may concern:

Be it known that I, SIVERT MOE, a citizen of the United States, and a resident of the city of Chicago, county of Cook, and State of Illinois, have invented certain new and useful Improvements in Mangles; and I do hereby declare that the following is a full, clear, and exact description of the same, reference being had to the accompanying drawings, 10 and to the letters of reference marked thereon, which form a part of this specification.

This invention relates to improvements in mangles and more particularly to a power operated mangle. In mangles of this class a large central drum or cylinder is heated by means of steam or in any suitable manner and a plurality of cloth covered pressure rolls are arranged longitudinally thereof and bearing upon its periphery and the fabrics to be mangled are passed between said drum and the rolls. In stopping all such mangles it is necessary that the pressure rolls be quickly raised from the heated drum to prevent the fabric burning, and where individual adjustment of each end of each of the pressure rolls is necessary considerable time is consumed which in many instances causes damage before the adjustment can be made. Furthermore when it is desired to start the 20 mangle it is obviously necessary to return the pressure rolls into engagement with the heated drum and when each pressure roll is thus individually adjusted it is difficult to get uniform adjustment at each end of the 25 rolls and with such machines the fabric is frequently drawn oblique on the heated roll tearing or injuring the same.

The object of this invention is to provide in combination with a mangle such as described, mechanism for instantaneously elevating each of the pressure rolls out of contact with the surface of the heated roll or drum and, furthermore to accomplish this adjustment either manually or by the power used to drive the machine. Furthermore to permit the pressure rollers to be returned into positive engagement with the drum simultaneously.

It is also an object of the invention to provide in conjunction with a mangle and adjusting means such as described, means for utilizing practically the entire periphery of the heated roll or drum at all times and to thoroughly dry the fabric after mangling.

It is a further object of the invention to provide a positively operated perfectly ad-

justable device of the class described in which the tension or pressure of the pressure rolls upon the heated drum is at all times uniform at both ends of each pressure roll, and for the 60 entire length of each pressure roll.

The invention consists in the matters hereinafter described and more fully pointed out and defined in the appended claims.

In the drawings: Figure 1 is a view in elevation taken at one end of a mangle embodying my invention. Fig. 2 is a fragmentary elevation of the opposite end of the machine. Fig. 3 is a view similar to Fig. 1 with the end frame member and adjusting mechanism removed. Fig. 4 is a view partly in side elevation and partly in vertical section of a device embodying my invention. Fig. 5 is an enlarged detail of one of the bearings for the end of the pressure rolls. Fig. 6 is an enlarged sectional detail of one of the lower pulleys for the conveying belt. Fig. 7 is an enlarged fragmentary detail of one of the adjusting shafts. Fig. 8 is a top plan view of the lower end of the same. Fig. 9 is an enlarged sectional detail of one of the adjusting rods and the bearing therefor. Fig. 10 is a detail of the adjusting mechanism.

In said drawings: A, indicates a hollow drum or cylinder of large diameter and of the desired length which is journaled at its ends a—a' to rotate in frame members B and B', each of which comprises a frame of the desired width and of a height to support the drum sufficiently above the foundation. 90 Above the bearing for said drum said frame members are each provided with an integral semicircular arch b which extends to the top of the drum and are constructed to afford great strength.

One of the hubs or gudgeons a', of said drum or cylinder is tubular communicating in the drum, and opening thereinto is an exhaust pipe a³, on the outer end of which is secured a casting or fitting a⁴, having an exhaust compartment therein in which said exhaust pipe communicates, and an inlet compartment therein from which an inlet pipe a⁵, extends through said exhaust pipe, and inwardly to near the periphery of the 105 drum. Said compartments are provided as shown, with an exhaust pipe and an inlet pipe respectively at all times in open communication with the corresponding pipes opening into the drum. A stuffing box or 110 gland is provided around the exhaust pipe in said hub to afford a tight joint.

Rigidly secured on the tubular hub a' , of said drum, is a gear C , of slightly less diameter than said drum. Journaled on the frame members $B-B'$ is a shaft C' , having a gear c , secured thereon and also a pinion c' , which meshes with the drum gear C . Said gear c meshes with a pinion c^3 , secured on a shaft C^2 , on which is secured the driving pulley c^2 , thereby communicating the drive to said 10 drum.

Mounted to slide radially in the upper arched portions b , of the end frame members, are supports D , one for each end of each of the pressure rollers D' , of which in the 15 present construction six are shown. Bearings or guides d are provided on each of said frame members as shown in Fig. 1, having inwardly directed grooves therein in which rest said bearing members or supports D . Each of said bearing members D is provided 20 at its upper end with a flat head d' , and with a longitudinal slot, as shown in Figs. 1 and 5, to receive the bearing block d^3 , for the guides of the pressure rolls, and engaging over 25 said flat head d' is a turret d^2 within which and bearing upon the bearing block d^3 , is a coiled spring d^4 , the tension of which is adjusted by means of a set screw d^5 , in the upper end of the turret.

Journaled on each hub of the drum A is a segment E which lie beneath the bearing arches b for the upper rolls, and which are provided with obliquely arranged slots e which extend in the same general direction 30 on the segments and from near the lower to near the upper edge, and in which engage pins e' secured in the supports D and each provided with a roller e^2 , thereon to reduce friction. Each of the segmental rings e^3 is 35 bolted to the frame and is provided with a groove e^4 and slots e^5 arranged concentrically with the hub. The hub e^6 of each segment E is provided with a rib e^7 which engages in said groove e^4 and bolts e^8 rigidly engaged to 40 the hub extend through said slots and hold the segment positively on the frame, but permit the same to rotate partly in either direction to bring the pins e' toward the inner ends of the slots, as shown in Fig. 1, to 45 draw the pressure rolls downwardly on the drum or toward the opposite ends of said slots to simultaneously elevate, all of the pressure rolls. Each of said pressure rolls, as shown, is provided at the extremity of its 50 shaft, as shown in Figs. 2 and 4, with a gear D^3 of greater diameter than the roll, and having long teeth which mesh with the gear C thereby driving said rolls therefrom and at a different peripheral speed from the drum 55 A . Means are provided for shifting both segments E simultaneously to adjust the rolls, comprising a shaft F , journaled longitudinally of the frame on the front and near the bottom thereof. This is provided with a

gear f thereon adapted to be actuated by a 60 worm f' , having a hand wheel f^2 thereon to rotate the same.

On the inner side of each frame member and secured on said shaft is a disk f^3 , on which is secured a wrist pin f^{20} , as shown in 70 dotted lines in Figs. 1 and 3, and engaged thereon and at the adjacent end of said segments E is a connecting rod F' which when said shaft is rotated by the worm in one direction shifts the segments to elevate the 75 rolls D' and when rotated in the other brings the rolls into positive engagement with the hot drum.

Means are provided for shifting the segments by power for this purpose, as shown, 80 the inner end of the worm shaft is journaled in a casing f^{19} which affords a bearing therefor and is bolted to the frame as shown in Figs. 1 and 4. A beveled gear f^4 is secured on the end of said shaft within the casing as 85 shown in dotted lines in Fig. 4 and rotatably secured on a transverse shaft f^5 , are beveled gears f^6 and f^7 intermeshing with opposite sides of the bevel gear f^4 through a slot in the casing as shown in Fig. 4. Said shaft f^5 as 90 shown is journaled at the end of the casing by means of removable bearing blocks which are bolted to said casing in a well known manner. The inner side of each of said beveled gears f^6-b^7 is shaped to afford one 95 member of a clutch, and feathered on the shaft f^5 , is a double clutch member f^8 , adapted to engage either of said beveled gears to rotate the shaft. A hand lever f^9 , having an arm f^{10} , thereon which at its end engages 100 said clutch member f^8 is pivoted on a boss f^{11} on the casing for the gear f^4 and the inner end of said lever f^9 is slidably engaged on a rod f^{12} , the upper end of which is pivotally engaged on the end of the segment E adjacent the connecting rod F' and the lower end extends below the lever f^9 , an adjustable stop f^{13} is secured on said rod above said lever and a stop f^{14} is pivoted at the lower end of said rod and hinged to bear at its 110 upper end against said rod below said lever f^9 , permitting a limited travel of the rod before engaging the lever f^9 . Said shaft f^5 , is positively driven by a sprocket chain f^{15} , trained around a sprocket wheel on said 115 shaft and one on the driving shaft C' .

Means are provided for utilizing practically the entire periphery of the drum continuously in mangling, for this purpose, as shown, a feed table G , is provided on one 120 side of the machine below the first roll and on the opposite side and at each end of the machine is pivoted a bell crank H , and on the outwardly directed arm thereof below the last roll, is journaled a pulley H^2 extending the length of the drum. Connected 125 on the other and downwardly directed arm of said bell crank is a connecting rod H' ,

one end of each of which engages a wrist pin f^{21} on said disk f^3 , which acts when the shaft F is rotated to elevate the pressure rolls to swing said pulley H^2 downwardly and inwardly. Beneath the feed table G is journaled a pulley of a length corresponding with the heating drum and indicated by h , and provided at its outer end with a gear h' , which meshes with a gear h^2 , on a shaft h^3 , the latter in turn meshing with a gear h^4 , on the driving shaft C . Trained about said pulleys is a belt h^5 equal in width to the length of said drum and the upper lap of which bears positively against the under side of the drum and the lower lap of which passes beneath a pulley h^6 , as shown in Fig. 3. A sprocket wheel h^8 is secured at each end of said pulley h^6 and on which engages a sprocket chain h^9 , one of which is permanently secured along each edge of the belt h^5 . A corresponding belt I^2 also provided along each edge with sprocket chains i , such as before described, is trained over a pulley I , adjustably supported on a bracket K , on one side of the frame and over a pulley I' secured on the shaft h^3 , before described, the upper lap of said belt passes beneath the pulley h^6 , and the lower lap of the belt h^5 , before described, as shown in Figs. 3 and 6; and the sprocket chains i on each margin thereof engage sprocket wheels i^4 , on each end of said shaft, as shown also the lower lap of said belt passes beneath the idlers i^2-i^3 , journaled at the bottom of the frame. All of said pulley shafts are provided at their ends with sprocket wheels to engage the sprocket chains secured at the edges of said belts similar to the arrangement shown in Fig. 6, and whereby the belts are positively driven and caused to run true about said pulleys without lateral slip, furthermore both belts are provided with tighteners, where the tension on the belt may be varied as desired. For this purpose the connecting rod H' at the point where the same engages the depending arm of the bell crank H , is provided with a spring L , which bears against the inner side of said arm and jam nuts l , whereby the tension on the lower end of said bell crank may be adjusted, thereby swinging the other end of the bell crank upwardly to tighten the belt. The tightener for the lower belt comprises at each side of the machine a screw shaft L' provided with an angular head for engagement with a suitable wrench. Said screw shaft engages in a suitable block which affords a bearing for the shaft of the pulley I and rotation of said shaft acts, to move the pulley inwardly or outwardly to loosen or tighten the belt.

As shown, a table M is positioned beneath the pulley I to receive the fabric after the same has passed through the machine and a

ledge or blade m extends upwardly from the edge of each table and bears lightly against the belt I^2 , as shown in Fig. 1, to strip the fabric therefrom.

The operation is as follows: The pressure rolls are each covered with fabric as usual, which for convenience is not shown, and are heated from contact with the hot drum. When it is desired to operate the machine the lever f^9 , is pressed down elevating its inner end and simultaneously throwing the clutch f^8 to engage the gear f^6 . The segments now start downwardly drawing the rolls upon the drum and the belt h^5 is simultaneously tightened by the outward swing of the bell cranks. When the segments reach the proper limit of travel the stop f^{13} engages the end of the lever f^9 shifting it to neutral position. If necessary the belt I^2 may be tightened by rotation of the screw shafts L' . Having adjusted the machine for operation (which can be accomplished almost instantaneously) the fabric is fed over the table G to the first pressure roll and is firmly pressed thereby and by succeeding rolls upon the heated drum and carried around the same and delivered between the same and the upper lap of the belt h^5 , and thence is carried between the lower lap of the upper belt and the upper lap of the lower belt, these being heated by mutual contact and contact with the heated drum continues the operation. The pressure rolls having a slightly different peripheral speed than the heated drum, the fabric is smoothed thereby and this action is continued in the travel of the fabric along the belts and at the delivery upon the table M the fabric is both smooth and dry.

Should at any moment it be desired to stop the operation of the mangle it can be instantly accomplished by lifting the lever f^9 to throw the clutch f^8 into engagement with the bevel gear f^7 , thus driving the worm and shifting the segments to elevate the rolls, and at the same time loosening the belt h^5 , permitting the same to sag away from the lower side of the heated drum, thus avoiding the burning of the fabric, either of the rolls or the belt, or any fabric in the mangles which may at that time be supported upon the upper belt. As the segments are elevated the top of the stop f^{14} , engages beneath the lever f^9 and shifts the same to neutral. Should it be desired the stop f^{14} may be turned back, as shown in dotted lines in Fig. 7, permitting the rolls to lift high enough to recover with fabric.

The belt can obviously never draw laterally on the pulleys because of the sprocket chains, at the margins thereof engaging over the sprocket wheels for said pulleys and of course any suitable means may be employed to tighten or loosen the lower belt as desired.

Obviously a machine such as described pos-

sesses great strength and the advantage of instant adjustability to enable an article to be instantly released from the mangle at any point in its passage therethrough. Of course, 5 the pressure rolls exert equal pressure throughout the length of the rolls. In consequence uniformity of action is insured and, there being no variation in the stress applied to the fabric passing therethrough, tearing 10 or injury of the fabric is practically an impossibility.

Obviously many details of construction may be varied. I therefore do not purpose limiting this application for patent otherwise 15 than necessitated by the prior art.

I claim as my invention:

1. In a device of the class described the combination with a frame of a heated drum journaled thereon, pressure rolls adapted to 20 bear on said drum, bell crank levers, one pivoted to each end of the frame, a pulley journaled thereon, a pulley journaled in said frame on the opposite side of the drum from the aforesaid pulley, a belt trained around 25 said pulleys and adapted to bear against the drum and mechanisms adapted to actuate said bell crank levers to release the belt from the drum and simultaneously move the rolls from contact with the drum.

30 2. In a device of the class described the combination with a frame of a drum secured thereto, pressure rolls adapted to contact the periphery of the drum, levers pivoted to said frame on one side of the drum, a pulley journaled on said levers, a pulley on the opposite side of said drum, a belt on said pulleys and bearing with its upper lap against the periphery of the drum, a belt contacting the lower lap of the aforesaid belt and means for 35 simultaneously actuating the levers to throw the belt away from the drum and to actuate 40 said pressure rolls.

3. In a device of the class described the combination with a frame of a hollow drum 45 engaged thereto, means for heating the same, pressure rollers adapted to contact said drum, a support for each end of each roll, a segment operatively connected with said supports adapted to actuate all of the 50 same simultaneously, a pulley journaled on each side of the drum, a belt thereon adapted to contact said drum and operative mechanisms adapted to simultaneously actuate said segment and to depress one of said pulleys to 55 move the belt and rolls out of contact with the drum.

4. In a device of the class described the combination with a main rotating drum of means for admitting a heating fluid thereinto, 60 a plurality of pressure rolls adapted to bear thereon, means actuating the pressure rolls from the main drum and at a different peripheral rate, a belt having one lap contacting the drum, rotative members connected

to simultaneously move the belt and rolls 65 into engagement with the drum and to simultaneously move the belt and rolls out of engagement therewith and means movable simultaneously with the rolls and belt for automatically limiting the adjustment thereof. 70

5. In a device of the class described the combination with a drum adapted to be heated of a plurality of pressure rollers adapted to bear against the same, segments, one connected with the rollers at each end adapted 75 to simultaneously actuate said rollers, a shaft, rods connected at their corresponding ends to the respective segment, rotatable members on the shaft connected with the appropriate rod, a shaft, rotatable members 80 thereon, a clutch and mechanism adapted to connect either member to rotate the first named shaft, a lever for shifting the clutch, a rod connected to one of the segments and means secured on said rod adapted to contact 85 the lever to automatically shift the clutch to neutral after the adjustment.

6. In a device of the class described the combination with a main rotating drum of means for heating the same, a plurality of 90 pressure rolls bearing thereon, cams acting to simultaneously shift said rolls from or draw the same into simultaneous engagement with the main drum, a shaft journaled longitudinally of the drum, disks thereon, 95 means connecting the respective disk and cam, a driven shaft extending approximately parallel with the aforesaid shaft and connected therewith, a clutch mechanism on said driven shaft adapted for adjustment to 100 actuate the cams to shift the rolls to or from the drum and operative connections between said cams and clutch adapted to automatically return the clutch to neutral 105 after the adjustment.

7. In a device of the class described the combination with a main heated drum of rolls adapted to contact the periphery thereof, coacting belts, one adapted to bear the fabric against the periphery of the drum and 110 said belts adapted to pass the fabric therebetween, mechanism adapted for manual actuation to simultaneously shift the rolls and one of the belts to and from the drum, a lever adapted to be operated to actuate mechanism 115 to shift the belt and rolls to and from the drum and means adapted to automatically limit the adjustment of the rolls and belt.

8. In a mangle, a main rotative drum adapted to be heated, a gear engaged to the 120 drum of slightly less diameter, pressure rolls bearing on the drum, a gear engaged to each pressure roll of greater diameter and each adapted to intermesh with the drum gear thereby driving the drum and rolls at different rates peripherally, cams acting to shift the gears out of and into meshing engagement and to move the rolls radially from the 125 .

- drum and draw the same thereto, a plurality of rods pivoted at the corresponding ends to one of said cams, means for actuating one of said rods to actuate said cam, means automatically actuated by the other rod to stop further movement of the cams after the desired adjustment is effected and means connecting the cams adapting both to move simultaneously.
- 10 9. In a device of the class described the combination with a frame of an arch integral therewith on each end thereof having apertures therethrough, a drum, means for heating the same, pressure rolls adapted to bear against the periphery of the drum, shafts for said rolls, slotted guides integral with said arch, a support extending through each aperture in the arch and through one of said guides, a bearing block at each end of each 15 roll shaft and movable in a slot in said support, a slotted cam movably secured to the frame, anti-friction means secured to each support and extending into the respective slot in said cam, a shaft below said cams, rods 20 connected to the cams and operatively connected with said shaft, a driven shaft extending parallel with the aforesaid shaft and adapted to actuate the same, a clutch secured to the driven shaft adapted to be adjusted to impart a motion in either direction 25 to the shaft connected with the rods and means carried by one of the cams to automatically return the clutch to neutral.
10. In a device of the class described the combination with a drum of means for heating the same, rolls adapted to be adjusted to and from the drum, cams for operating said rolls simultaneously, an upper belt having its upper lap bearing against said drum, a 30 lower belt having its upper lap bearing against the lower lap of the upper belt, means for adjusting the tension of the lower belt, means for adjusting the tension of the upper belt, disks having operative connections 35 with the upper belt and with the cams, a clutch mechanism for operating the disks in either direction to simultaneously move the upper belt and rolls to contact the drum or vice versa and means operated by one of 40 the cams to automatically limit the movement of the rolls and belt.
11. In a device of the class described the combination with a drum of means for heating the same, rolls adapted to contact said 45 drum, segments operatively connected with the rolls to simultaneously adjust all of the same, pulleys journaled longitudinally of the frame, levers supporting one of said pulleys, an upper belt on said pulleys adapted to contact the drum, a lower belt adapted to contact the upper belt, rods operatively connected at one end to said levers, tension 50 means on said rods adapted to adjust said levers to vary the tension of the upper belt,
- a rod engaged to each segment, means connected with the rods to simultaneously actuate the rolls and upper belt and means automatically limiting the movement of the rolls and belt.
12. In a device of the class described the combination with a drum of means for heating the same, rolls adapted to bear against said drum, slotted segments operatively connected with the rolls, an upper belt adapted to bear against the drum, a lower belt coacting therewith, an independent mechanism for varying the tension of each belt, a shaft journaled on said frame, disks thereon, a shaft journaled transversely thereof, intermeshing gears on said shafts, a bevel gear on 80 the last named shaft, a casing around the same, a driven shaft journaled thereto, bevel gears thereon intermeshing with the aforesaid bevel gear, a clutch mechanism adapted to engage either bevel gear on the driven shaft for operating the disks in either direction, connecting rods operatively connected with the segments and with the upper belt at one end and at their opposite ends pivoted to said disks thereby adjusting the rolls and 90 belt synchronously and mechanism adapted to automatically return the clutch to neutral after the disks have moved the required distance.
13. In a device of the class described the combination with a main rotating drum adapted to be heated, of a plurality of rolls adapted to contact the same peripherally, means driving the drum and rolls at different rates of speed peripherally, pulleys journaled longitudinally of the drum, coacting belts thereon one of which is adapted to bear against the drum, sprocket wheels journaled on each end of said pulleys, a sprocket chain rigidly secured to each side of 105 each belt and trained over the respective wheels and means simultaneously shifting all of the rolls and the belt adapted to contact the drum.
14. In a device of the class described the combination with a drum of means for heating the same, a plurality of rolls adapted to bear on the periphery of the drum, a segment supporting the same at each end, a bell crank lever at each end of the drum, a pulley 110 journaled on the short arms of said levers, a pulley journaled to the frame, an upper belt on said pulleys, a lower belt coacting with said upper belt, sprocket wheels on each pulley, sprocket chains on each edge of the belts 115 adapted to engage thereon, a rod connected with the long arm of each bell crank lever, a rod connected with each segment and means operatively connected with all of said rods for actuating the rolls and upper belt simultaneously.
15. In a mangle embracing a main rotative drum, pressure rollers adapted to con-

tact the periphery thereof and simultaneously adjustable to and from the drum, a belt adapted to receive the material treated from the rolls and bear it against the drum, bell cranks on which one of the pulleys for the belt is journaled, cams for elevating the rolls, a shaft, disks thereon, connecting rods connected on wrist pins on each disk and one connected with an arm of the appropriate bell crank, the other with the appropriate cam, a clutch acting to drive said shaft in either direction and an adjusting rod movable with the cams and engaging the shifting lever for the clutch, and means for manually actuating said disks.

16. In a device of the class described the combination with a drum adapted to be heated of a plurality of rolls adapted to bear against the same, segments having cam slots therein, a support for each roll, a pin secured to each support adapted to project through one of said slots, rods engaged to said segments, a shaft, disks thereon connected with said rods, a driven shaft, bevel gears thereon, a clutch adapted to engage either gear and operative connections between said gears and disks adapted when the clutch engages one or the other of said gears to elevate or depress said rolls depending upon the gear engaged.

17. In a device of the class described the combination with a drum adapted to be heated of a plurality of rolls adapted to bear against the same, segments, supports for each roll engaged at one end by said segments, pulleys, coacting belts thereon one of which is adapted to bear against the drum, a shaft, disks thereon, rods, one connecting

each segment to one of said disks, and one of which affords connection between the disk 40 and one of said pulleys and adapted when said disks are actuated to simultaneously adjust said rolls and belt to or from the drum.

18. In a device of the class described the combination with a drum adapted to be heated of a plurality of rolls adapted to bear against the same, pulleys journaled longitudinally of the drum, belts carried thereon, one of which is adapted to bear against the drum, bell crank levers engaged to one of 50 said pulleys, slotted segments, a support for each roll engaged at one end in one of said slots, disks, rods connected thereto, one at each end of the machine engaged to the appropriate segment and one to the appropriate 55 bell crank lever and mechanism adapted to move said disks to simultaneously adjust the rolls and said belt to and from the drum.

19. In a device of the class described the combination with a drum of a plurality of 60 rolls adapted to contact the same, cam segments operatively connected with said rolls, a belt adapted to bear against said drum, manually operated means adapted to simultaneously adjust said belt and rolls to or 65 from the drum, a lever adapted for manual actuation and means for shifting said belt and rolls to contact said drum or vice versa upon actuation of said lever.

In testimony whereof I have hereunto subscribed my name in the presence of two subscribing witnesses.

SIVERT MOE.
